UNITED STATES PATENT OFFICE.

JULES A. MUSSILLON, OF SPRINGFIELD, ILLINOIS.

DESIGN FOR A KNOB-TURNER.

No. 39,960.

Specification for Design.

Patented May 4, 1909.

Application filed February 23, 1909. Serial No. 479,665. Term of patent 7 years.

To all whom it may concern:

Be it known that I, JULES A. MUSSILLON, a citizen of the United States, residing at Springfield, in the county of Sangamon and State of Illinois, have invented a new, original, and ornamental Design for Knob-Turners, such as are used for turning the knobs of permutation-locks of safes or the like.

Following is a specification of my said design, reference being had to the accompanying drawing, forming part thereof.

The design comprises a structure 1 of approximately annular contour and having parallel extensions 2 and 2'. The extension 2 is given a quarter turn to form a horizontal

member 2'', the juncture of the member 2'' with the member 2 being of curved outline as shown. A handle 3 occupies a vertical position on the member 2. In the upper and lower edges of the structure 1 are a plurality of indentations 4 giving to the structure 1 an ornamental scalloped appearance as shown.

I claim:

The ornamental design for a knob turner as shown and described.

JULES A. MUSSILLON.
